Application filed February 15, 1932. Serial No. 42,881. Term of patent 14 years.

To all whom it may concern:

Be it known that we, THOMAS J. McCORMICK and ROBERT E. LINN, both citizens of the United States, residing at Detroit, in the county of Wayne and State of Michigan, have invented a new, original, and ornamental Design for Tire Covers, reference being had to the accompanying drawing, forming part thereof.

Figure 1 is a perspective view of the tire cover, showing our new design.

The dominant feature of our design consists of the body portion of dark material contrasting in color with the two highly polished concentric rings or beads, one of which is shown at the outer circular edge of the front face and the other of which is shown at the inner circular edge of the front face.

What we claim is:

The ornamental design for a tire cover, substantially as shown and described.
